UNITED STATES PATENT OFFICE.

CHARLES E. WHITMARSH, OF NEW YORK, N. Y., ASSIGNOR OF THREE-FOURTHS TO JOHN GOURLAY AND JOHN J. O'BRIEN, OF SAME PLACE.

BICYCLE-LAMP BRACKET.

SPECIFICATION forming part of Letters Patent No. 623,453, dated April 18, 1899.

Application filed March 25, 1898. Serial No. 675,187. (No model.)

To all whom it may concern:

Be it known that I, CHARLES E. WHITMARSH, of the city of New York, borough of Brooklyn, in the county of Kings and State of New York, 5 have invented a new and Improved Bicycle-Lamp Bracket, of which the following is a full, clear, and exact description.

My invention relates to an improvement in bicycle-lamp brackets, having for its object 10 the formation of a swinging support for the lamp, which will enable the lamp to swing into any position necessary and thus to remain at all times in an upright position.

My invention consists of the novel features 15 of construction which will be hereinafter described and claimed.

Reference is to be had to the accompanying drawings, forming a part of this specification, in which similar characters of reference indicate 20 corresponding parts in all the figures.

Figure 1 is a side elevation of a bicycle-head, showing the bracket attached thereto and a portion of a lamp. Fig. 2 is a vertical section through the bracket. Fig. 3 is a front 25 view of the same, and Fig. 4 is a top plan view.

With ordinary fixed brackets for bicycle-lamps it often occurs that when the bicycle is in a leaning position the lamp will smoke or have the oil run out of the same due to the 30 inclined position of the lamp. The object of my invention is to cure this trouble by having the arm upon which the lamp is secured suspended upon a pivot, so that the center of gravity of the lamp is beneath the pivot, and 35 it will thus at all times maintain an upright position.

My bracket is divided into two principal parts, one consisting of the disk A, which is provided with means for securing it to the 40 bicycle, and the other the complementary disk B, which carries the arm upon which the lamp is secured. These two disks are preferably provided with ball-bearings E between the same, so that the disks may rotate 45 with as little friction as possible. While the ball-bearing is a preferred feature, it is not strictly essential, as an ordinary bearing will in a measure accomplish the same purpose. The essential object desired is to form a pivot 50 which shall cause as little friction as possible

and which extends in substantially a horizontal position. As the device is attached to the steering-head of a bicycle, the pivot will not be strictly horizontal, but will be slightly inclined. This, however, is near enough to 55 a horizontal position to answer the purpose.

The disk A is provided with some form of clamp by which it may be secured to that portion of the bicycle-frame upon which it is desired to support the lamp. The clamping 60 mechanism herein shown consists of the band C, which is adapted to surround the head H and has its ends brought together by a clamping-bolt C'. The inner surface of this clamp is lined with a layer G of leather, felt, or similar substance adapted to protect the bicycle-frame from injury by contact with the band. If the bracket is to be attached to some other portion of the frame, a clamping device suitably constructed for such purposes is to be 65 substituted for the ring C. The two adjacent faces of the disks A and B are provided with circular grooves adapted to receive the balls E, and the two disks are held together by a bolt F, which passes through one disk and 70 screws into the other. The clamping-band C is secured to the disk A or to the bolt F, as shown in the drawings, by means of a small 75 screw or in any other suitable manner.

The two disks A and B are preferably in- 80 cased in a circular band D, which prevents access of dirt to the ball-bearings. To the disk B is attached an arm I by means of pins f or by other suitable means. This arm extends forward and downward and is adapted to enter the socket L, provided upon bicycle-lamps for that purpose. The lamp may be secured upon this arm by turning the set-screw M, which is usually provided upon such lamps. To insure the lamp against jarring off the 90 bracket, the arm is preferably provided with a spring J at the lower end of the arm and which extends upwardly and at a slight angle from the arm. Intermediate its length this spring is provided with a shoulder or 95 bend K, which is adapted to engage the lower side of the socket L, and thus prevent any possibility of the lamp dropping off of the arm. When the bracket is inserted in the lamp-socket, the spring J is forced against 100

the bracket until it has passed far enough through the socket to clear the shoulder K. It then springs out, so as to engage the under side of the socket and prevent the lamp from falling off. This pivotal suspension of the lamp will hold the lamp always in an upright position no matter what may be the position of the bicycle. The lamp will therefore not be as liable to smoke as it will where it is held 10 in an inclined position.

Having thus fully described my invention, I claim as new and desire to secure by Letters Patent—

1. A bicycle-lamp bracket, comprising two parts rotatable one upon the other by a pivot extending longitudinally of the bicycle, one part being attachable to the bicycle and the other having a depending arm, and means for securing a lamp to said arm, substantially 15 20 as described.

2. A bicycle-lamp bracket, comprising two parts rotatable one upon the other, one part being attachable to the bicycle and the other having a depending arm, said arm having a spring-catch located at its lower end, and a shoulder formed upon said catch intermediate its length and adapted to engage the lower edge of the lamp-socket, substantially as described. 25

3. A bicycle-lamp bracket, comprising two parts rotatable one upon each other, one part being attachable to the bicycle and the other having a depending arm provided with a spring-catch engageable with the lamp-socket, substantially as described. 30
